COMBINED CRIB AND STORAGE UNIT

John W. Tapert, 2381 Earhart Road, Ann Arbor, Mich.

Filed Feb. 27, 1964, Ser. No. 78,795

Term of patent 14 years

(Cl. D5—5)

FIGURE 1 is a front perspective view of a combined crib and storage unit showing my new design;

FIGURE 2 is a top plan view, on a reduced scale of the combined crib and storage unit shown in FIGURE 1;

FIGURE 3 is a bottom plan view thereof, on a reduced scale; and

FIGURE 4 is a side elevational view on a reduced scale.

The appearance of the end of the combined crib and storage unit not shown in FIGURE 4 is the same as that of the end shown therein, and the appearance of the rear of the combined crib and storage unit not shown in FIGURE 1 is the same as that of the front shown therein.

I claim:

The ornamental design for a combined crib and storage unit, substantially as shown and described.
